Patented June 6, 1916.

FIG. 1.

UNITED STATES PATENT OFFICE.

FORREST L. CUMMINS, OF LAKEVIEW, OHIO.

SASH-HOLDER.

1,186,380.

Specification of Letters Patent.

Patented June 6, 1916.

Application filed August 6, 1915. Serial No. 44,038.

To all whom it may concern:

Be it known that I, FORREST L. CUMMINS, a citizen of the United States, residing at Lakeview, in the county of Logan, State of Ohio, have invented certain new and useful Improvements in Sash-Holders; and I do hereby declare the following to be a full, clear, and exact description of the invention, such as will enable others skilled in the art 10 to which it appertains to make and use the same.

The present invention is directed to improvements in sash holders, and has for its object to so construct a device of this character 15 that the sash can be held in adjusted positions without the aid of weights and cords.

A further object of the invention is to provide a sash holder so constructed that the 20 same will effectually hold a window sash in different adjusted positions, and further to provide a holder which is exceedingly simple in construction.

A still further object of the invention is to 25 provide a sash holder which frictionally engages the side rails of the sash to hold the same in adjusted positions.

With these and other objects in view, this invention resides in the novel features of 30 construction, formation, combination and arrangement of parts to be hereinafter more fully described, claimed and illustrated in the accompanying drawing, in which:—

Figure 1 is a front elevation of a portion 35 of a window frame, parts broken away, and showing the holder in place thereon. Fig. 2 is a sectional view on line 2—2 of Fig. 1. Fig. 3 is a similar view on line 3—3 of Fig. 1. Fig. 4 is a detail perspective view of one 40 of the holding bars.

Referring to the drawing 1 indicates the window frame, which has its sides provided with sash grooves 2. Opening into the grooves 2 of one side of the frame, are slots 45 3, the purpose of which will appear later.

The holding bars 4 are formed from wood, and are provided with shoulders 5, said shoulders being disposed adjacent the ends of the slots 3, and serve to prevent vertical 50 movement of the bars. By providing the

shoulders 5, extensions 6 are provided, said extensions being formed with perforations 7, which receive the bolts 8, and have their inner ends engaged with the sides of the frame 1, and their outer ends projected beyond the extensions 6 after passing through the perforations 7 formed therein. The projected ends of the bolts 8 are encircled by coil springs 10, which have their inner ends engaged with the extensions 6, and their outer ends with the adjusting nuts 11, said nuts being operable to regulate the tension of the springs 10, and thus the frictional engagement of the bars with the side rails 12 of the sashes 13. The inner edges of the bars 4 have metal strips 14 secured thereto. 60

The side rails of the sashes are provided with metal strips 15, which have secured thereto strips of felt 16 or the like, and since the same engage the strips 14, it is obvious 65 that the frictional engagement between said strips will be sufficient to hold the sashes in adjusted positions.

It will be of course obvious that both sides of the window frame may be provided with 70 holding bars, if desired.

What is claimed is:—

In a sash holder, the combination with a window frame having its sides provided with sash engaging grooves, holding bars 80 having extensions formed upon their ends to provide shoulders, said window frame having slots formed in the sides, said bars being projected into the slots with the shoulders disposed adjacent the ends of the slots and 85 slidably engaged therein, bolts carried by the sides of the frame and projected through said extensions, and coil springs encircling the projected ends of the bolts, and having their inner ends engaged with the extensions, 90 nuts engaged upon the bolts and engaged with the outer edge of the coil spring, sashes slidable in the grooves of the frame and frictionally engaged by said bars.

In testimony whereof, I affix my signature, in the presence of two witnesses.

FORREST L. CUMMINS.

Witnesses:

MERLE MC GUIRE,
BERTHA C. ARMSTRONG.
